[57] CLAIM

The ornamental design for a tie or similar article, as shown.

DESCRIPTION

FIG. 1 is a front elevational view of a tie or similar article showing my new design;

FIG. 2 is a left side elevational view thereof, the right side being a mirror image;

FIG. 3 is a front elevational view of a tie or similar article showing a modified form of my new design;

FIG. 4 is a left side elevational view thereof, the right side being a mirror image; and

FIG. 5 is a top plan view of both embodiments.

The broken line showing of neckband is for illustrative purposes only and forms no part of the claimed design.

FIG 1

FIG 2

FIG 4
